BOX MACHINE

Ernest G. Rider and Walter T. Bailey, Philadelphia, Pa., assignors to Stokes and Smith Company, Summerville, Pa., a corporation of Pennsylvania

Application October 16, 1935, Serial No. 45,247

8 Claims. (Cl. 93—54.2)

Our invention relates to apparatus for covering previously formed or stayed boxes, containers, or the like, by applying thereto a wrapper, label, or equivalent, or for forming a box from a single or multipiece box blank by applying sheet material, as a tabbed or untabbed wrapper, or tabs solely, previously partially applied or adherent to the box blank, to hold the box elements in box-forming position, and particularly to box machines of the type having a reciprocating form block which carries the box structure through various sheet-applying and/or staying stages.

In accordance with our invention, the operating mechanism for the form block structure is constructed either to complete the movement of the form block from and back to its box-receiving position in substantially less than the cycle of the machine or to move slowly toward the sheet-applying or wrapping tools, to provide a substantial period during which a box structure and adhering sheet material may be placed upon the form block, and the mechanism for effecting the various box-wrapping or forming operations while the form block is away from the box-receiving position includes tools, more specifically corner-lap tools, whose operation does not require interruption of the movement of the form block.

Our invention further resides in the features of construction, combination and arrangement hereinabove described and claimed.

This application is a continuation-in-part of our copending application Serial No. 17,018, filed April 18, 1935.

For an understanding of our invention and for illustration of preferred forms thereof, reference is to be had to the accompanying drawings in which:

Figure 1 is a front elevational view, with parts omitted and parts in section, of a box wrapping machine;

Fig. 2 is a side elevational view, with parts omitted and parts in section, of Fig. 1;

Fig. 3 is a plan view of parts appearing in Fig. 2;

Fig. 4 is a side elevational view, on enlarged scale and with parts in section, of one of the tool slides of Fig. 1;

Fig. 4a is a detail view showing mechanism of Fig. 4 in a different operating position;

Fig. 5 is a detail view of a modified form of wrapping tool;

Fig. 6 is a plan view of Fig. 5;

Fig. 7 is a plan view of Fig. 4 with parts in section and parts omitted;

Fig. 8 is a detail view showing a modified form of folding mechanism;

Fig. 9 is a plan view of Fig. 8;

Fig. 10 illustrates the parts of Fig. 8 in different operating positions;

Fig. 11 is a side elevational view with parts in section of another type of tool slide;

Figs. 12 and 13 illustrate the relations between the movements of the form block and the movements of the various wrapping tools throughout the cycles of different modifications.

The wrapping machine shown in Figs. 1 and 2 is, in general, similar to that shown in Smith Patent No. 691,329. The form block F for carrying a box and wrapping assembly into operative relation with respect to various wrapping tools is operated by the main cam 1 secured to the upper end of shaft 2 which is driven from any suitable source of power connected to the shaft 2 through pulley 4, clutch 3 and shaft 5.

As the form block moves downwardly, the box blank and wrapper are clamped against the lower form block or platen P biased by a spring, not shown, to the position shown in Fig. 1. For continued downward movement of the form block, the rolls 6, 6a wipe the side panels of the wrapper into engagement with the side walls of the box.

As indicated by Fig. 2 the action of the rolls may be supplemented by the brushes 7, 7a. As the form block continues its downward movement, the corner-lap tools 8, 8a fold the flaps at the ends of the side panels of the wrapper around the corners of the box into engagement with the box ends; subsequently, the rolls 9, 9a, Fig. 1,

wipe the end panels of the wrapper into engagement with the end walls of the box and the turned-in flap of the wrapper side panels. The form block continues its movement until the upper part UF thereof is slightly above the marginal turn-in tools 10, 10a, 10b and 10c, for example, approximately one-half inch. The upper part UF of the block is then stopped under the control of the cam groove 11 of cam 1 while the middle part MF continues downward until the upper edge of the box is slightly below the turn-in tools, whereupon the groove 12 of cam 1 temporarily stops movement of the box. The turn-in tools 10—10c then move to turn in the marginal portions of the wrapper extending above the edge of the box and substantially concurrently the tools 13—13c move inwardly lightly to press the sides of the box against the form block. The upper portion UF of the form block is then released and when the tools 10—10c

are withdrawn, the upper portion of the form blocks falls to fold the marginal portions of the wrapper into engagement with the inside of the box. The pressing tools 13—13c are then again actuated more heavily to press the sides of the box against the sides of the form block to insure a good bond between the box and the marginal turned-in portions of the wrapper.

The various tools are then withdrawn and the plunger moves upwardly toward its original position. As the form block leaves the platen P, the strippers SB controlled by cam groove 11 of the main cam 1 remain stationary to prevent the completed box from following the form block to its box-receiving position. When the form block has moved out of the box, the strippers SB are rapidly lifted clear of the box and thereupon the ejector J is automatically fired, forcibly to remove the completed box from the machine.

Heretofore, in machines of this type, exemplified by the aforesaid Smith patent, the cam 1 did not effect return of the form block to its box-receiving position until nearly the end of the cycle of the machine, leaving a dwell of not more than about 30° which, unless the machine were run slowly, did not afford time enough for an operator to place another box thereon. Moreover, with the prior machines, much less than all of the 30° dwell was available at box-feeding time since the strippers did not clear the box until about 345°, and the ejector did not fire until after about 360°. With the machine operating at a low speed corresponding to about 20 boxes per minute, the operator had therefore only about 0.1 second during which the form block was accessible to receive a box. It was not feasible to operate the machine at speeds higher than about twenty cycles per minute because the operator did not then have sufficient time to place a box on the form block.

With our improvements hereinafter described, the wrapping operations are performed in a smaller fraction of the cycle, permitting, in accordance with a preferred form of the invention, (Fig. 12), the form block to be returned to its original box-receiving position in time to afford during the cycle of the machine a dwell substantially greater than 30° and practically all of which is available for box-feeding. Specifically, as hereinafter appears, the preferred construction affords a dwell of the form block of about 65°; during about 40° of this dwell, the form block is accessible to receive a box. With the machine operating at a high speed, corresponding, for example, to about 30 boxes per minute, the operator therefore has about 0.4 second during which the form block is accessible to receive a box. A minimum feeding time of about 0.1 second may be obtained, at such higher speed, with a shorter dwell, but it is desirable that a longer box-feeding period be provided to compensate for the increased burden upon the operator of feeding a substantially increased number of boxes. Consequently, the operator, when our improved machine is running, for example, at a speed corresponding to 30 boxes per minute, has, in each cycle, a period, for placing a box on the form block, which is several times as long as the period available for that purpose with a machine of the prior type operating at a low speed of only 20 boxes per minute.

As appears from Figs. 1 and 2, the various wrapping tools are carried by the four slides ES, ESI, SS and SSI, which are adjustably secured to the under side of the table 14 of the

wrapping machine. Specifically, the slides are received by grooves in the underside of the table and are supported by the gibbs 15, Fig. 1. For different sizes of boxes, different sizes of form blocks and platens are used; and to accommodate the machine for wrapping different sizes of boxes, the slides are adjustable toward and from the path of the form block.

The internal construction and operating mechanism for the side slide SS is shown in Fig. 4. The construction of the opposite slide SSI is identical and is, therefore, not separately shown. The slide is made in two halves, as shown in Fig. 7, which are clamped together to provide a housing 18 in which most of the operating mechanism is disposed. The vertically reciprocable member 17 is adjustably secured as by clamping screw 18 to the bar 19 extending radially from the member 20 which is slidable upon the fixed cylinder 21 which receives the plunger 22 for supporting platen P. The reciprocable member 20 is connected by link 20a to lever 23 pivoted at 24 to the bracket 25 fastened to the framework of the machine. The other end of lever 23 carries a cam follower 26 which is received by the cam groove 27 of the cam 28 which is secured to shaft 2. Accordingly, as shaft 2 rotates to effect reciprocation of the form block of the wrapping machine, the members 17 of the tool slides SS and SSI operate in predetermined time relation thereto. The end slides ES and ESI are also each provided with a reciprocable member 17 similarly operable from cam 28.

Reverting to Fig. 4, the upper end of the member 17 carries a pin extending through the slot 29 in a link 30 pivotally connected to one arm of the bell-crank lever 31 which is pivoted at 32 to a bracket 33 of the tool slide. The other arm 34 of the bell-crank lever is connected by link 35 to the slidable frame 36 which carries the roll 6 and brush 7. As shown in Figs. 3 and 4, the slidable frame 36 is guided for reciprocation toward and from the path of the form block by the guide members 37 which receive the rods 38 of the frame 36. The groove of cam 28 is so shaped that the roll 6 and brush 7 are moved inwardly prior to descent of the form block from the position shown in Fig. 1 to apply a wrapper side panel, as above described, and are retracted as the form block moves upwardly toward the position of Fig. 1. The timing diagram of Fig. 12 illustrates the relation between the movements of the form block and the side tools 6, 7.

The member 17 is provided with a cut-out portion or slot in which a gear 39 is disposed. The pin 40, secured to the sides of member 17, provides the support for the gear 39. As shown in Fig. 4, on one side of its axis the gear 39 is in mesh with the stationary rack 41 and on the other side of its axis is in mesh with the rack 42 secured to or integral with the slidable member 43. Accordingly, as the member 17 is reciprocated the slidable member 43 is reciprocated to greater extent since the rack and gear arrangement described provides a motion-multiplying connection. The cam groove 44 in one face of the reciprocable member 43 engages the cam follower 45 at one end of the bell-crank lever 46 pivotally mounted on a stub shaft secured to one side of the slide. The other arm of the bell-crank lever 46 is connected by link 47 to the slidable member 48 which carries the frame 49 for the presser block 13. Preferably, and as shown, the presser block is not rigidly secured to the frame 49 but is

capable of relative motion. The spring 56 biases the presser block to the position shown in Fig. 4 and permits it to yield when moved into engagement with a box to effect the pressing operation 5 above described.

As shown in Fig. 7, the frame 48 for the presser block is guided for reciprocating movement by the rods 81 which extend therefrom into the guide members 62 carried by the main frame 10 of the slide.

The opposite face of the slidable cam member 43 is provided with the cam groove 53 which receives the cam follower 54 carried by one arm of the bell-crank lever 55 whose other arm is 15 connected by link 56 to the slidable member 57 which carries a pin 58 extending through a slot 59 in the frame 60 for the marginal turn-in tool 10. The spring 61 biases the frame 60 to the position shown in Fig. 4. The frame 60, as more 20 clearly shown in Fig. 7, is guided for movement toward and from the path of the form block by the rods 62 which are received by the guide members 63 on the main frame of the slide unit.

The mechanism for operating the marginal 25 turn-in tools and presser blocks of the end slides ES and ES¹ is substantially the same as that shown in Fig. 4. The arrangement for operating the end rolls 8 and 8a, as clearly appears in Fig. 1, is generally the same as that for operating 30 the side rolls 6, 6a, the principal difference being that the brackets 33 of the end slides are substantially lower since the rolls 8 and 8a are much closer to the marginal turn-in tools than are rolls 6 and 6a of the side slides. Corresponding elements of the operating mechanism for the side slides have been identified by the same reference characters with suitable subscripts.

Referring to Fig. 4, the side slides carry the corner-lap tools 8, 8a for folding the end flaps 40 WE into engagement with the box ends BE. Each of the side slides SS, SS¹ is provided with a bracket 64 for supporting a shaft 65 to which the pairs of folding tools are secured. The relation 45 between the tools and the form block is clearly shown in the right half of Fig. 3. The arm 66 secured to shaft 65 is connected to the lever 67, which is pivoted to the frame of the slide, by a yielding connection which permits the lever 67 to move after the abutment 68 of arm 66 engages the adjustable stop 69 on bracket 33. More specifically, as shown in Fig. 4, to the lever 67 is pivotally connected the hollow member 69 which receives one end of rod 70 whose other end is pivoted to arm 66. A spring 71 between the collar 55 12 on rod 70 and the plug 13 of member 69 biases the parts to the position shown. When lever 67 is moved in counterclockwise direction, the tool 8 is swung in clockwise direction to meet the box and wrapper assembly; specifically, the tip of 60 each of the corner-lap tools 8 meets a corner flap of the wrapper adjacent its lower edge, shortly after the bottom of the box moves below rolls 6, 6a and moves downwardly with the form block until the lever 67 is arrested by the stop 68. As 65 the form block continues its movement the tools remain in this position. Thus, the end flaps of the wrapper side panels are wiped intimately into engagement with the box end. With the construction shown, the movement of the form block 70 from the position shown in Fig. 1 to the position adjacent the marginal turning tools is continuous; there is no pause in the movement of the form block during the turning in of the wrapper flaps WE by tools 8.

75 As it appears from Fig. 4, the wrapping tools 8

may be pivotally mounted at the ends of arms 74 on shaft 65, the springs 75 permitting them to yield and afford wiping action during the corner-lap operation.

The operating shaft for the lever 67 is connected through a universal joint with the shaft 76, whose other end is connected through a universal joint to shaft 77 supported by the bracket 78, secured to the main framework of the machine. Arm 79 secured to shaft 77 is connected by link 80 to the lever 67 pivoted on the bracket 82 and whose arm 83 carries the cam follower 84 which is received by the groove 53 of cam 56 secured to shaft 2. The arm 67a, not shown, of the opposite slide unit SS¹ is similarly connected to the lever 67, the corresponding connecting elements being identified by like reference characters with suitable subscripts.

The cam 56 is adjustably secured to the shaft 2 to accommodate the machine for wrapping boxes of different sizes. As shown in Fig. 1, an index or pointer on cam 56 may cooperate with a scale 81 calibrated for different box sizes. This adjustment is necessary, since whatever may be the depth of the box, the form block must stop when the box is positioned so that its upper edge is opposite the marginal turning tools 10-10c. Therefore, the time in the cycle of form block movement at which the bottom of the box passes the folding tools 8, 8a is different for different sizes of boxes.

If desired, the folding tools 8, 8a may be provided with brushes to effect the wiping action. As shown in Figs. 5 and 6, the plate 87, to which is secured a row of bristles 88, is adapted to be attached to the wiping plate of a folding tool 8. Plate 87 may, as shown, be provided with holes 89 matching holes 90 in tool 8 to permit clamping bolts to be passed therethrough.

When the box blanks are unstayed, and particularly for making extension bottom boxes from unstayed blanks, it is desirable that the side walls of the box be supported or held against the form block during the folding of the wrapper end flaps by the tools 8. As shown in Figs. 8 to 10, there 40 may be associated with each of the folding tools 8 a side supporting tool 91 pivotally mounted upon a block 92 which is adjustably secured to a bar 93 carried by the tool slide. The under surface of the member 91 is provided with a cam 45 surface cooperating with an abutment 94 movable with a tool 8. When the tool 8 is in its retracted position, the side supporting tool 91 is held by the pin 94 out of the path of the form block. As the tool 8 swings inwardly to perform 50 the wiping operation, the side supporting tool 91 also moves inwardly, the pin 94 and the cam surface of the member 91 controlling the relative 55 positions of the folding tool and the side supporting tool during this movement. When the side supporting tool 91 reaches the position shown in Fig. 10 in which it is holding the side wall of the box against the form block, the rear extension 95 thereof engages the shoulder 96 of the supporting bracket and its further movement 60 is arrested. The wiping tool, however, as shown by Fig. 10, continues to move downwardly with the form block and thus moves pin 94 out of engagement with the tool 91. The side supporting tool moves the side wall of the box into proper 65 position and insures intimate engagement of the wrapper with the box adjacent the corner. As the folding tool 8 returns to its original position, the pin 94 again engages the supporting member 91 and returns it to the position shown in Fig. 8. 70

For extension bottom work, the side roll 6, in accordance with the usual practice, is provided with a cutout or groove and is spring-biased to the position shown in Fig. 8.

The improved construction of the mechanism for operating the wrapping tools makes possible significant changes in the timing of various elements of the machine. Cam grooves 11 and 12 may be constructed so that the movement of the 10 form block structure F from and to its box-receiving position is completed in substantially less than the complete cycle of the machine, (Fig. 12). Specifically, the form block is returned to the box-receiving position at about 295° of the cycle, 15 Fig. 12, having a dwell of about 65° as contrasted with the dwell of only 30° in the machine disclosed in the aforesaid Smith Patent No. 691,329. The cam groove 12 effects continuous movement of the form block from the box-receiving position 20 to the margin turn-in position, there being no dwell for operation of the corner-lap tools. Moreover, the fraction of the cycle for which the form-block is stationary for the margin turn-in operation and the pressing operations is substantially 25 reduced, the dwell provided by cam groove 12 for these operations being only about 100° as compared with about 140° of the aforesaid Smith machine.

The shape of the cam groove 11 is also modified 30 to effect completion of the box-stripping operation by tools SB at about 320°, Fig. 12, whereas, in the aforesaid Smith machine the stripping tools were not clear of the box until about 345°. With the improved construction, the action of 35 the ejector J is also substantially advanced, affording about 40° of the cycle in which the form block is in box-receiving position and free of obstructions or accessible to receive a box.

With our improved machine, the speed can be 40 substantially increased and yet afford in each cycle ample time for an operator to place a box on the form block, whereas, with the construction shown in the Smith patent, it was necessary either to operate the machine at slow speed, or 45 to permit it to stop at the end of each cycle in order to afford sufficient time for an operator to place a box and wrapper assembly on the form. The substantially increased dwell of the box-block in box-receiving position is also of advantage 50 when the boxes are fed automatically to the form block.

Furthermore, as appears from Fig. 12, the cam groove 12 may be so constructed that the form-block moves relatively slowly when moving downwardly toward the wrapping tools so that even if the form-block has begun to descend, the operator can still place a box on the form-block. The feeding time is thus actually greater than the time afforded by the dwell of cam 12. Also as 60 shown by Fig. 12, the form-block is moved rapidly upwardly after the box has been completed.

As appears from Fig. 13, the prolonged feeding period may be obtained with a short dwell of the form-block by further reducing the speed at 65 which the form-block is moved downwardly toward the wrapping tools since this increases the time during which the form block is in the clear above the slide units. The figure is self-explanatory and requires no further description particularly in view of the discussion of Fig. 12.

In Fig. 11, there is illustrated the application of our new type of "non-stop" corner-lap construction to tool slides for wrapping machines of the type disclosed and claimed in Federwitz application Serial No. 757,115, filed December 12, 1934,

and generally of the type shown in Nitsch et al. Patent No. 1,540,900. In this construction, the main cam 1a of the wrapping machine is in the base and drives the shaft 87 individual to the slide units, one of which is shown. Shaft 87, 5 through gears 88, 89, drives the cam 100 to which cam 28a is adjustably secured. The lever 101 which corresponds to lever 67, of the modification previously described, is provided with a cam follower 102 for the cam groove in cam 28a. The 10 principal difference between this modification and that previously described, insofar as the mechanism for operating the corner-lap tools is concerned, is that, in this modification, each of the 15 side slides is provided with a cam for operating the two corner-lap tools of the slide, whereas, in the wrapping machine of Fig. 1, a single cam 86 controls the operation of both sets of corner-lap tools. The corresponding elements have been 20 identified by the same reference characters used in describing the construction and operation of the modification of Figs. 1 to 10.

The modification of Fig. 11 also permits the timing of the machine elements to be changed to afford a long box-feeding dwell in the cycle of 25 the machine. In general, the timing diagram of the machine may be substantially the same as that shown in Fig. 12 or Fig. 13.

While we have illustrated and described preferred arrangements, it is to be understood our 30 invention is not limited thereto, but is coextensive in scope with the appended claims in which, for brevity, the term "wrapping" is used generically to comprehend the application of wrappers, tabbed, or untabbed, or of stayng or tabbing 35 material, and the term "box" is used generically to comprehend a stayed, or unstayed, box, a box blank, or one or more components of a multi-piece box blank.

What we claim is:

1. A box machine adapted to repeat its cycle continuously at high speed comprising reciprocating form-block structure, corner-lap tools, mechanism for operating said tools while said form-block structure is in motion, and mechanism including cam structure for operating said form-block structure providing, in the cycle of the machine, a period of dwell or slow motion of said form-block structure, of not less than about 40° of said cycle, for application of a box structure thereto. 50

2. A box machine adapted to repeat its cycle continuously at high speed comprising reciprocating form-block structure, corner-lap tools, mechanism for operating said tools while said form-block structure is in motion, turn-in and pressing tools, mechanism for operating said last-named tools while form-block structure is at rest, and mechanism cam structure for operating said form-block structure providing for slow motion 55 thereof during its travel toward said corner-lap tools, for more rapid motion during its travel from said turn-in and pressing tools and a dwell of said form-block when in box-receiving position of not less than about 40° of the cycle of 60 said machine. 65

3. A box machine adapted to repeat its cycle continuously at high speed comprising reciprocating form-block structure, corner-lap tools, mechanism for operating said tools while said form-block structure is in motion, turn-in and pressing tool, mechanism for effecting completion of the operation of said last-named tools in about 100° of a cycle of the machine, and mechanism including cam structure for reciprocating said 70 75

form-block structure and providing a period for application of a box-structure to the form-block structure which is not less than about 40° of the cycle of said machine.

5. A box wrapping machine comprising reciprocating form-block structure, corner-lap tools, turn-in tools, mechanism including cam structure for moving said form-block structure from box-receiving position without interruption to a 10 position adjacent said turn-in tools, and for providing a period of dwell or slow motion of said form-block structure of not less than about 40° of said cycle for application of box structure, and mechanism for actuating said corner-lap tools 15 to effect their operation during movement of said form-block structure toward said turn-in tools.

5. A box wrapping machine comprising reciprocating form-block structure, corner-lap tools, turn-in and presser tools, mechanism including 20 cam structure for moving said form-block structure from box-receiving position without interruption to a position adjacent said turn-in tools within about 120° of the cycle of said machine, and for providing a dwell of said form-block structure, for application of box structure, of not less than about 40°, and mechanism for actuating 25 said corner-lap tools to effect their corner-lapping operation during movement of said form-block structure toward said turn-in tools.

30. 6. A box wrapping machine comprising reciprocating form-block structure, corner-lap tools, turn-in and presser tools, mechanism including cam structure for reciprocating said form-block structure and constructed to provide a period of 35 slow motion or dwell of said form-block structure, of not less than about 40° of said cycle, for application of a box structure, continuous movement of said form-block structure from box-receiving position to a position adjacent said turn-

in tools, and a dwell of said form-block structure of about 100° for operation of said presser and turn-in tools, and mechanism for actuating said corner-lap tools to effect their corner-lapping operation during movement of said form-block structure toward said turn-in and presser tools. 5

7. A box wrapping machine comprising reciprocating form-block structure, corner-lap tools, turn-in and presser tools, mechanism including cam structure for reciprocating said form-block 10 structure and constructed to provide a dwell of less than about 40° and a period of slow motion of not less than about 40° for application of a box structure, continuous movement of said form-block structure from box-receiving position to a position adjacent said turn-in tools, and a dwell of said form-block structure of materially less than 140° for operation of said presser and turn-in tools, and mechanism for actuating said corner-lap tools to effect their corner-lapping operation during movement of said form-block structure toward said turn-in and presser tools. 15

8. A box wrapping machine comprising reciprocating form-block structure, corner-lap tools, turn-in and presser tools, mechanism including cam structure for moving said form-block structure from box-receiving position without interruption to a position adjacent said turn-in tools in about 160° of the cycle of said machine, and for providing a dwell of said form-block structure of about 100° for operation of said turn-in and presser tools, and mechanism for actuating said corner-lap tools to effect their corner-lapping operation during movement of said form-block structure toward said turn-in tools. 20 25 30 35

ERNEST G. RIDER.

form-block structure and providing a period for application of a box-structure to the form-block structure which is not less than about 40° of the cycle of said machine.

5. A box wrapping machine comprising reciprocating form-block structure, corner-lap tools, turn-in tools, mechanism including cam structure for moving said form-block structure from box-receiving position without interruption to a 10 position adjacent said turn-in tools, and for providing a period of dwell or slow motion of said form-block structure of not less than about 40° of said cycle for application of box structure, and mechanism for actuating said corner-lap tools 15 to effect their operation during movement of said form-block structure toward said turn-in tools.

5. A box wrapping machine comprising reciprocating form-block structure, corner-lap tools, turn-in and presser tools, mechanism including 20 cam structure for moving said form-block structure from box-receiving position without interruption to a position adjacent said turn-in tools within about 120° of the cycle of said machine, and for providing a dwell of said form-block structure, for application of box structure, of not less than about 40°, and mechanism for actuating 25 said corner-lap tools to effect their corner-lapping operation during movement of said form-block structure toward said turn-in tools.

30. 6. A box wrapping machine comprising reciprocating form-block structure, corner-lap tools, turn-in and presser tools, mechanism including cam structure for reciprocating said form-block structure and constructed to provide a period of 35 slow motion or dwell of said form-block structure, of not less than about 40° of said cycle, for application of a box structure, continuous movement of said form-block structure from box-receiving position to a position adjacent said turn-

in tools, and a dwell of said form-block structure of about 100° for operation of said presser and turn-in tools, and mechanism for actuating said corner-lap tools to effect their corner-lapping operation during movement of said form-block structure toward said turn-in and presser tools. 5

7. A box wrapping machine comprising reciprocating form-block structure, corner-lap tools, turn-in and presser tools, mechanism including cam structure for reciprocating said form-block 10 structure and constructed to provide a dwell of less than about 40° and a period of slow motion of not less than about 40° for application of a box structure, continuous movement of said form-block structure from box-receiving position to a position adjacent said turn-in tools, and a dwell of said form-block structure of materially less than 140° for operation of said presser and turn-in tools, and mechanism for actuating said corner-lap tools to effect their corner-lapping operation during movement of said form-block structure toward said turn-in and presser tools. 15

8. A box wrapping machine comprising reciprocating form-block structure, corner-lap tools, turn-in and presser tools, mechanism including cam structure for moving said form-block structure from box-receiving position without interruption to a position adjacent said turn-in tools in about 160° of the cycle of said machine, and for providing a dwell of said form-block structure of about 100° for operation of said turn-in and presser tools, and mechanism for actuating said corner-lap tools to effect their corner-lapping operation during movement of said form-block structure toward said turn-in tools. 20 25 30 35

ERNEST G. RIDER.
WALTER T. BAILEY.

CERTIFICATE OF CORRECTION.

Patent No. 2,074,561.

March 23, 1937.

ERNEST G. RIDER, ET AL.

It is hereby certified that error appears in the printed specification of the above numbered patent requiring correction as follows: Page 4, second column, line 63, claim 2, for the word "well" read dwell; and that the said Letters Patent should be read with this correction therein that the same may conform to the record of the case in the Patent Office.

Signed and sealed this 20th day of July, A. D. 1937.

Henry Van Arsdale

Acting Commissioner of Patents.
